8 Claims. (Cl. 104—173)

The invention relates to a slope ascending apparatus of the type more often named a "ski-lift" which pulls along skiers or toboggans or other sledges carrying a person or a load.

The object of the invention is to provide a light ski-lift which can be easily brought to the place of use, mounted and dismounted, presents no danger even for children, can be easily shifted, and is furthermore relatively cheap, these various advantages rendering this apparatus a ski-lift of utility for a small group of persons, for example a family.

Another object of the invention is to provide a ski-lift of this type which, while meeting these requirements can nonetheless pull several persons up an ascending slope at normal speed over a distance of about several hundred metres and even about one kilometre.

The ski-lift according to the invention which meets said requirements comprises: a chassis, slide members solid with said chassis whereby the latter can slide on the snow and the ground, a motor rigidly fixed on said chassis, a drive pulley rotatively mounted on said chassis, gear means operatively connected with said motor and said drive pulley, an end pulley spaced from said chassis, removable chassis anchoring means for anchoring said chassis in the snow or the ground, removable pulley anchoring means for anchoring said end pulley in the snow or the ground, an endless cable extending round said drive pulley and said end pulley, at least one friction-operated hooking device for detachably hooking a load at any point of said endless cable, and an automatic disconnecting device comprising a helical spring encompassing said cable and having one end bearing on a fixed part of said chassis and the other end being directed upstream relative to the movement of said cable within said spring, for automatically disconnecting from said cable said hooking device when the latter, at the end of its travel, engages said free end of said spring.

Another object of the invention is to provide a ski-lift comprising: a chassis, slide members solid with said chassis whereby the latter can slide on the snow and the ground, a motor rigidly fixed on said chassis, a drive pulley rotatively mounted on said chassis, gear means operatively connected with said motor and said drive pulley, an end pulley spaced from said chassis, removable chassis anchoring means for anchoring said chassis in the snow or the ground, removable pulley anchoring means for anchoring said end pulley in the snow or the ground, an endless cable extending around said drive pulley and said end pulley, and at least one hooking device; said hooking device comprising: a flat support having a plane face, two substantially circular projections solid with said support on said plane face, said projections having the shape of V-groove pulleys whose axes are perpendicular to said plane face and being spaced apart such a distance as to allow said cable to be introduced between said projections, the dimensions of the grooves of said V-groove pulleys being such as to allow wedging said cable in said grooves, a lever arm extending laterally of said support, solid with the latter, said lever arm having a longitudinal axis parallel with said plane face and contained in the symmetry plane perpendicular to the line passing through the centers of said two projections; said

2

ski-lift further comprising an automatic resilient disconnecting device fixed on said chassis and encompassing said cable to automatically disconnect from said cable said hooking device when the latter, at the ends of its travels 5 engages said disconnecting device.

Said arm is provided at its end with an eye for securing said device to a stick held by the user or to some other load, such as a toboggan or sledge.

In the course of operation of the apparatus this cable 10 may be required to pull along a widely varying total load which depends in particular on the number of skiers or on the weights of the inert loads hooked to the cable.

The resistant torque applied by the cable on the motor of the apparatus is variable and it is therefore necessary 15 that the driving torque of the apparatus be constantly regulated to the value of this resistant torque.

This regulation can be effected in the well-known manner by means of devices which vary with the type of motor used and which can comprise, for example, a device 20 regulating the applied voltage if it concerns an electric motor, or a device regulating the admission of the gases if it concerns an internal combustion motor.

In any case, this regulation is carried out by mechanically acting on a control, for example a rod, which acts 25 on the regulating device proper, for example on the throttle valve of the carburetor.

This regulation can be controlled manually with the same ease as on a motor vehicle, but this requires the constant presence of an operator next to the ski-lift.

30 Another feature of the invention is the provision of a device whereby the driving torque is regulated automatically when the load applied to the ski-lift varies.

According to a modification of the invention, the anchoring means of the apparatus, enabling the latter to 35 resist the traction of the moving cable, is secured not to the chassis of the apparatus but to an element elastically movable relative to the chassis so that the chassis can move relative to the anchoring means in opposition to the elastic action, said element being connected to the control controlling the torque of the motor of the apparatus so that when, under the effect of a variation in the traction exerted by the cable, the apparatus moves away from or towards its anchoring means said element undergoes a relative displacement relative to the chassis 45 and shifts said control of the motor, said shifting being a function of the displacement of the apparatus relative to the anchoring means.

Said element elastically movable relative to the chassis can be a link pivotally mounted on the chassis at one of 50 its ends, the other end of the link being movable and operatively connected to an elastic element which latter is connected to or bears against the chassis, said movable end of the link being connected to said control of the motor.

55 Said elastic element can be, for example, a helical spring working under compression or extension.

The anchoring means is preferably connected to said link at a point intermediate of the two ends of the latter so that a small displacement of the apparatus relative to 60 the anchoring means, which creates a small displacement of the point of attachment of the anchoring means to the link, produces a greater displacement of the movable end of the link and consequently of said control of the motor.

65 The apparatus is preferably mounted on a support facilitating its movement over the ground under the effect of a traction on the cable; for example, the apparatus can be mounted on skis.

70 Further features and advantages of the invention will be apparent from the ensuing description, with reference to the accompanying drawings to which the invention is in no way limited.

In the drawings:

FIG. 1 is a plan view of the general assembly of one embodiment of a slope ascending apparatus of the ski-lift type according to the invention, the apparatus being in its working position;

FIG. 2 is a perspective view on an enlarged scale of one of the individual hooking devices of utility in the ski-lift shown in FIG. 1;

FIGS. 3 and 4 are views of the motor chassis, namely a side elevational and a plan view respectively;

FIG. 5 is a detail view of the automatic driving torque-regulating system;

FIG. 6 is a sectional view of a disconnecting device which is a part of the ski-lift of the invention;

In the embodiment shown in FIGS. 1 to 6, the ski-lift according to the invention comprises a fixed unit which is anchored in the ground or snow but is easily removed therefrom. This unit (FIG. 1) comprises a motor chassis 1 anchored by anchoring means in the form of a three-pronged fork 2 the prongs of which are inclined downwardly towards the ground in the direction of the traction exerted on this anchoring means, an endless cable 3 driven by the motor on the chassis 1, an end pulley 4 round which passes the end of the loop formed by the cable, said pulley being freely rotative on a sheaf 5 to which is connected a spring 6 connected to an anchoring means in the form of a three-pronged fork 7 similar to the fork 2. This cable has an ascending side 3a and a descending side 3b; it can be held taut in a straight line between the chassis 1 and the extreme point 8 of the travel, but preferably a sheaf 10 carrying a pair of pulleys 11, is anchored at this point 8 by means of a three-pronged fork 9, the end pulley 4 merely insuring that the cable is kept under tension.

The forks 2, 7, 9 can be replaced by any other anchoring means having a sufficient number of prongs and sufficient surface to afford a suitable anchoring. Prongs 30 cm. in length are normally sufficient in the case of a small apparatus.

The motor chassis 1 comprises an independent motor, for example an internal combustion motor of sufficient power but light enough to permit the unit 1 to be easily moved over the snow. For example, this unit 1 can include a motor weighing about 3 kg., the weight of the unit being about 10 kg.; it can then be mounted on skis and pulled along by hand. If the slope and the number of users require a more powerful motor, a heavier unit may be needed, for example weighing about 20 kg.

The distance between the driving station 1 and the point 8 can vary to a very large extent in accordance with the nature of the ground and other considerations affecting the length of the required travel; the length of the cable 3 is arranged accordingly.

The cable is so chosen as to have an amply sufficient strength.

It can be seen that this apparatus has no element to be permanently secured in the ground and in particular no support posts. The cables lie on or in the snow or at certain points are held at a small height above the latter. The apparatus can therefore be used on slopes which vary widely and on stretches of ground having very great variations in slope.

The motor unit 1 can in any case be installed at the upper or lower end of the slope.

According to an important feature of the invention the users or the loads to be drawn along can be hooked onto the cable by means of an individual hooking device 12 shown in FIG. 2, without providing this cable with any attachment means such as loops, knots, hooks or other elements of any kind projecting from the cable.

This device comprises a support plate 13 provided with two bosses or projections 14a, 14b in the form of pulleys rigidly secured to the support plate or preferably moulded or cast in one piece therewith. These circular projections are provided on their periphery with grooves 15a, 15b

having V-shaped sections whose dimensions suit the diameter of the cable. An arm 16 contained in the same plane as the plate 13 is fixed to the plate in the plane of symmetry of the latter. Preferably, the arm 16 is also moulded or cast in one piece with the plate 13. It has at one end an eye 17 to which can be secured a connection 18 for attaching the device 12 to a rigid element, such as a stick of a skier which pulls the latter along, or to for example a toboggan or sledge.

10 This device operates in a simple manner:

Assuming that the ascending side 3a of the cable 3 is driven for example in the direction of the arrow F₁ (FIG. 2), if the device 12 is placed in the position I, that is, in such manner that the cable passes between the two projections 14a, 14b, the arm 16 extending in a direction parallel with the cable, namely that indicated by arrow F₁, it is clear that the device 12 will not be driven by the cable; on the other hand, if the arm 16 is rotated, for example in the direction of arrow F₂ approximately about an axis parallel with the axes of the projections and midway between the latter, the cable is wound round a portion of an arc of each of the projections 14a, 14b. As will be understood, owing to the frictional contact created a driving force will result which very rapidly increases with increase in the value of the angle pertaining to the winding of the cable round the projections, this driving force being proportional to the value of the force applying the cable in the grooves of the projections. This force is itself a function of the resistance R applied to the end of the arm 16 multiplied by the ratio OA/OB, in which OA and OB are respectively the distances from the point O (which is midway between the centres of the two projections) to the centre A of the eye 17 and to the centre B of one of the projections 14a or 14b.

It is thus easy to obtain a considerable frictional force between the device 12 and the cable, this force acting in the manner of a wedge, since if the resistance R (which depends on the weight of the load drawn along, the value of the slope, the condition of the supporting surfaces, the state of the snow, etc.) increases, the adherence of the cable to the projections increases, on the one hand, because the cable is applied more heavily in the grooves, and on the other hand, because an increase in the resistance causes the arm to pivot rearwardly and this increases the angle of winding of the cable round the projections.

There is thus obtained an automatic regulation of the force connecting the device 12 to the cable; in the driving position (FIG. 2), the arm 16 therefore occupies a position II of equilibrium which is not necessarily perpendicular to the general direction of the cable as shown at II in FIG. 2 but which can assume any position of equilibrium forward or rearward of this position depending on the value of the load to be drawn along.

55 To disconnect the cable from the load (for example constituted by the skier), it may be sufficient to cease to apply the resistance R, for example by releasing the stick hooked to the connection 18 or by detaching the connection 18 from the sledge. The released device 12 then pivots under the effect of the traction of the cable and falls away from the latter. However, due to the wedging effect exerted by the V-shaped grooves on the cable, it is preferable to provide this ski-lift with an automatic disconnecting device which will be described hereinafter.

60 It will be clear that the load may be hooked to the cable in pivoting the device 12 in the direction F₃ instead of the direction F₂ or if this device was placed on top of the cable or on the side thereof. It follows that the user can take up a position on either side of the cable.

65 This connecting device 12 is of utility not only in the ski-lift according to the invention but also whenever a load must be detachably secured to a driven cable in the course of movement of the latter, this cable having no projection, hook or other attaching device.

The motor unit 1, which constitutes the means retaining and driving the cable, can be constructed in various ways. One embodiment (to which the scope of the invention is not limited) is shown in FIGS. 3-6. In this embodiment the unit comprises a tubular chassis 1 formed by a bent tube or several portions of tubes united by welding or otherwise.

This stand carries an internal combustion motor 25 which could be, for example, a motorcycle motor which has a power rating of a few H.P. and is fixed or suspended from the chassis by tubes or elastic suspension devices. This motor drives through the medium of a gearbox 26, a shaft 27 carrying a pulley 28 provided with at least one groove coated with a lining of rubber or other material having a high coefficient of friction. The endless cable 3 passes round this pulley which is driven in the suitable direction. Reference character 3a denotes the ascending side and 3b the descending side of the cable.

Preferably, in order to increase the value of the angle of winding of the cable, the pulley 28 has two grooves 28a, 28b, the cable passing successively in the groove 28a, round a pulley of small diameter 29, and then in the groove 28b; the directions of winding between the pulleys 29 and 28 are preferably reversed so as to still further increase the angle of winding.

Depending on its type, the motor can be provided with a change gear device (not shown) controlled manually or with an automatic variator automatically regulating the value of the driving torque in accordance with the resistant torque.

The ascending side 3a of the cable passes through an elastic disconnecting element 33 shown in FIG. 6 and comprising a sleeve 34 in which is disposed a helical spring 35 which carries an inlet member 36 in the form of a funnel. This elastic disconnecting element 33 is 35 detachably secured to a tube 37 by means of rapid coupling device 38, such as a screw-and-nut or bayonet connection, these two types of connection being conventional and currently used in pipe connections.

The operation and the manner of using this ski-lift will be clear from the foregoing description. When a hooking device 12 drawing along its load reaches the end of the travel of the cable, it encounters the inlet element 36. The shock occurs on the leading edge of plate 13 which thus encounters the abutment element 36. The hooking device 12 driven by the cable in the direction F₁ (FIG. 2) presses on the element 36 and compresses the spring 35 (FIG. 6) while exerts on the device 12 an increasing reaction resulting in a torque which opposes the torque generated by the traction cable 18. The device 13 tends to pivot towards the position shown at the right in FIG. 2, in which position, obviously, no wedging effect is generated; when or before this position is reached, the spring abruptly expands and casts the device away from the cable, thus automatically disconnecting the device from the cable.

When it is desired to remove the cable, the device 33 is released from the chassis almost instantaneously by unscrewing the cap of the connection 38 or turning the fixing element of the bayonet connection.

The invention therefore provides an apparatus having the aforementioned advantages. Owing to the ease with which it is mounted and dismounted, the apparatus can be placed in position at the start of each period of use and removed at the end of this period.

Therefore, outside the periods of use the apparatus can be sheltered from bad weather and requires but very little maintenance.

It will be observed that the cable carries no member which is permanently secured thereto; such members constitute a certain danger which is therefore avoided in the apparatus according to the invention.

The motor in this embodiment is an internal combustion motor (not shown in the drawing) and the rod controlling the fuel throttle valve is connected to a finger 51

or the like, so that an action exerted on this finger controls the position of the throttle valve, a rearward traction (in the direction of arrow F₄) opening the throttle valve, that is to say, increasing the driving power of the motor.

The chassis is mounted on a pair of skis 52.

Pivoted at 53 to the lower part of the stand or, as shown in the drawing, to the ski situated on the same side as the cable 3, is a link 54 whose upper end 55 is pivoted to a rod 56 extending through a horizontal tube 57 welded to the stand 1. The portion 56a of the rod 56 remote from the pivot 55 is screwthreaded and provided with a wingnut 58 which acts as an abutment for a coil spring 59 partly disposed in the tube 57 and compressed between the nut 58 and the bottom of this tube.

The free end of the rod 56 is connected to the finger 51 controlling the throttle valve.

The link 54 is provided toward its lower part with one or several holes (two holes are shown), such as 60a and 60b, disposed at different distances from the pivot 53. Secured in one of these holes (60b) is a fork 61 to which is pivoted the end of the rod 62 of an anchoring means 63 similar or identical to the fork 2 described hereinbefore.

25 This apparatus operates in the following manner:

When no load is carried or when the cable 3 is subjected to a light traction, the link 54 occupies for example the position 54-I shown in full line in FIG. 5 and corresponding to an idle speed of the motor.

30 If the resistant force applied to the cable increases, the chassis slides in the direction of arrow F₅ (FIG. 5), but the point 60b remains fixed since it is connected to the anchoring means whereas the point 53 moves slightly in the direction of arrow F₅. The link 54 therefore assumes the position shown in dot-dash line at 54-II and the spring is slightly compressed. It is clear that as the point 60b is further away from the pivot 55 than from the pivot 53, the distance the pivot 55 travels through is greater than the distance the chassis travels through relative to the ground. Thus a small displacement of the chassis creates a greater displacement of the rod 56 and consequently of the element 51 controlling the throttle valve.

The displacement of the element 51 in the direction of arrow F₄ corresponds to a greater opening of the throttle valve and consequently an automatic increase in the value of the driving power of the motor.

When the tractional force applied on the cable decreases, the chassis is returned rearwardly by the spring 59, the rod 56 moves in the direction opposed to that of arrow F₄ and the throttle valve of the motor closes to an extent depending on the displacement of the chassis.

The adjustment of the action of this device for a given load can be effected, on the one hand, by regulating the position of the nut 58 and, on the other hand, by selecting among the holes 60a, 60b . . . the suitable hole for fixing the fork 61. In selecting a hole which is further away from the pivot 53, the action on the throttle valve is reduced for a given displacement of the chassis.

60 Changing the position of the fork 61 from one hole to another acts in a manner comparable with the passage of one speed to another of the gearbox of a conventional motor vehicle.

65 Although specific embodiments of the invention have been described, many modifications and changes may be made therein without departing from the scope of the invention as defined in the appended claims.

For instance, the motor is not necessarily independent and can consist for example of an electric motor fed by mains supply or some other source of current; this is a possible solution in the case of a ski-lift for a hotel for example.

70 The automatic power regulating device is also applicable to a unit provided with an injection engine (such as a diesel engine) or an electric motor, the element 51 being

in each case a suitable element acting on the control controlling the driving power; this power regulating device is also applicable to a unit mounted on wheels or articulated tracks. If the unit is not sufficiently sensitive to the traction of the cable, the sensitivity can be increased by suitably preparing the ground on which the unit is placed or by disposing under this unit an intermediate support, such as a floor or floor-boards facilitating the sliding of the unit.

Having now described my invention what I claim as new and desire to secure by Letters Patent is:

1. Ski-lift comprising: a chassis, slide members solid with said chassis whereby the latter can slide on the snow and the ground, a motor rigidly fixed on said chassis, a drive pulley rotatively mounted on said chassis, gear means operatively connected with said motor and said drive pulley, an end pulley spaced from said chassis, removable chassis anchoring means for anchoring said chassis in the snow or the ground, removable pulley anchoring means for anchoring said end pulley in the snow or the ground, an endless cable extending round said drive pulley and said end pulley, at least one friction-operated hooking device for detachably hooking a load at any point of said endless cable, and an automatic disconnecting device comprising a helical spring encompassing said cable and having one end bearing on a fixed part of said chassis and another end being directed upstream relative to the movement of said cable within said spring, for automatically disconnecting from said cable said hooking device when the latter, at the end of its travel, engages said free end of said spring.

2. In a ski-lift comprising: a chassis mounted on slide members to slide on the snow or the ground, a motor fixed on said chassis, said motor having a power-control device and a control member connected with said power-control device and movable relative to said chassis, a drive pulley rotatively mounted on said chassis and operatively connected with said motor to be driven by the latter, an end pulley spaced from said chassis, first removable anchoring means for anchoring said end pulley in the snow or the ground, an endless cable extending round said pulleys to be driven by said drive pulley, and at least one detachable hooking device for hooking a load at any point of said endless cable; second removable anchoring means, connecting means connected with said second anchoring means and said control member, and spring means interposed between said chassis and said connecting means to oppose and limit the displacements of the chassis caused by the reaction of the cable when the latter is loaded.

3. Ski-lift according to claim 2 wherein said connecting means comprise a rocking member pivotally connected, at a first point thereof, with said chassis, at a second point, spaced from said first point, with said second anchoring means, and at a third point, with a rod connected to the control member of the motor.

4. Ski-lift according to claim 3 wherein said spring means is a helical spring.

5. Ski-lift according to claim 4 wherein said helical spring encompasses said rod, is partially housed in a tube fixed on the chassis, and is compressed between said chassis and a nut screwed on a threaded portion of said rod.

6. Ski-lift according to claim 3 wherein the distance between said first and third points is larger than the distance between said first and second points.

5. 7. Ski-lift according to claim 3 wherein said rocking member has a number of holes positioned at different distances from said first point, and said second anchoring means can be connected with said rocking member at any of said holes, whereby the distance between said first and second points can be varied.

8. Ski-lift comprising: a chassis, slide members solid with said chassis whereby the latter can slide on the snow and the ground, a motor rigidly fixed on said chassis, a drive pulley rotatively mounted on said chassis, gear means operatively connected with said motor and said drive pulley, an end pulley spaced from said chassis, removable chassis anchoring means for anchoring said chassis in the snow or the ground, removable pulley anchoring means for anchoring said end pulley in the snow or the ground, an endless cable extending around said drive pulley and said end pulley, and at least one hooking device; said hooking device comprising: a flat support having a plane face, two substantially circular projections solid with said support on said plane face, said projections having the shape of V-groove pulleys whose axes are perpendicular to said plane face and being spaced apart such a distance as to allow said cable to be introduced between said projections, the dimensions of the grooves of said V-groove-pulleys being such as to allow wedging said cable in said grooves, and a lever arm extending laterally of said support, solid with the latter, said lever arm having a longitudinal axis parallel with said plane face and contained in the symmetry plane perpendicular to the line passing through the centers of said two projections; said ski-lift further comprising an automatic resilient disconnecting device fixed on said chassis and encompassing said cable to automatically disconnect from said cable said hooking device when the latter, at the ends of its travels engages said disconnecting device.
